ABSTRACT OF THE DISCLOSURE

Spectrometry apparatus consists of a vacuum chamber, an electron and X-ray emission tube, a sample-holder, a device provided with slots, an analyser crystal and means for measuring an electrical value, a vacuum pump and means for introducing a gas inside the tube. The external envelope of the emission tube contains a quartz tube placed concentrically and a cathode and an anode both centred by means of said quartz tube; a tubular socket closes the open end of the external envelope while the quartz tube and the socket are provided, adjacent of the anode, with lateral apertures on the same axis; a capillary duct permits the introduction of a gas to the neighbourhood of said apertures; and servo-operating means permits the control of the flow of gas by the flux of electrons emitted by the anode.

The present invention relates to a spectrometry apparatus and more particularly to a tube for the emission of X-rays and electrons, the latter by back-scattering from the anode.

Crookes X-ray tubes used for the emission of X-rays a filament emitting electrons by thermo-electric effect. The electrons thus emitted are accelerated in a linear electrical field and come to strike a target which, in its turn, emits an X radiation characteristic of the target with a constant background which becomes greater as the acceleration voltage increases. This emission takes place in a high vacuum of about 10^{-5} torr. It is, furthermore known that the ionising effect in gas, described in particular by Gordon Francis in "Ionisation Phenomena of Gases," London, 1960, Butterworth edition, in which an electron having sufficient energy ionises a gas, causes a multiplication of the current which becomes greater as the electric field increases. The theory of this phenomenon has been described by MacAfee, in his paper on "Phenomena in Ionised Gases," presented at the 7th Belgrade Conference in 1965.

It is already known to use in spectrometry the back-scattering phenomenon in which an electron striking an anode emits a beam of electrons of lower energy depending both on the nature of the anode and on the energy of the incident electrons. As a result of the random variations of the emitted flux of electrons, the electrical current which strikes the anode is not stable.

It was furthermore known to adjust the pressure of the gas in the emission tube by means of adjustable input injections.

The subject of the present invention is a spectrometry apparatus comprising an emission tube operating in vacuum of from 10^{-2} to 10^{-3} mm. Hg having a value comparable to that existing in the spectrometer chamber and permitting the simultaneous use of X-rays and electrons scattered by the anode due to the absence of a window between the wall of the tube and the sample to be analysed.

The special equipment of the tube enables the operator

2

to attain the aims of the invention through a simple and easy-to-build construction.

The spectrometry apparatus according to the invention is more specially characterised in that it is provided with an emission tube, the external tubular envelope of which contains a quartz tube placed concentrically and a cathode and an anode both centred by means of said quartz tube; a tubular socket closing the open end of the external envelope, the quartz tube and the socket being provided in their parts adjacent to the anode, with lateral apertures having the same axis; a capillary duct for the introduction of a gas to the neighborhood of said apertures, and servo-operating means for the control of the gas flow by the flux of electrons emitted by the anode.

15 The servo-system can consist of a proportionally adjustable solenoid valve placed upstream on the capillary duct and which is servo-controlled by one of the electronic parameters of the tube, such as the current potential, so as to provide the stability of the current of electrons delivered.

20 According to one embodiment of the invention, an ammeter connected between the anode and the cathode permits the measurement of the flux of electrons emitted by the anode, the measured current controlling a proportionally adjusted solenoid valve placed upstream on said capillary duct, the servo-control taking place under conditions leading to the stabilisation of the current.

25 According to another embodiment of the invention, a collector receives a part of the flux of electrons emitted by the anode, and the charge collected by the collector servo-controlling the solenoid valve permits the adjustment of the gaseous flow in the capillary tube.

30 According to a further embodiment of the invention, a low-energy X-ray detector measures the flux of X-rays emitted by the anode and servo-controls the gaseous flow adjustment solenoid valve.

35 According to a still further embodiment of the invention, an X-ray detector receiving the rays emitted by the analysed sample indirectly measures the flux of electrons and enables the control of the servo-operating solenoid valve.

40 The active part of the cold cathode can be made of high purity aluminium, whereas the active part of the anode is made of an appropriate metal, such as tungsten, rhenium, molybdenum, niobium, tantalum or platinum.

45 The invention will be better understood in the description hereunder of an embodiment illustrated by the two attached drawings.

50 FIG. 1 shows a diagram of the X-ray and electron emission tube.

FIG. 1A shows the target end of the tube connected to a micro-ammeter for measuring the current between the anode and cathode.

55 FIG. 1B shows the target end of the tube associated with X-ray responsive means for controlling the gas flow.

FIG. 2 shows a diagram of an X-ray assembly comprising said X-ray and electron emission tube.

A hollow cylindrical tube 1 is provided coaxially with a cylindrical member having a substantially smaller diameter 2, fitted over part of its length with cooling fins 3. In one end of the tube 1 is a quartz tube 4 for electrical insulation of member 2. The member 2 is provided with a pellet of pure aluminium 5, screwed, for example, onto the end of the cylindrical member 2, which is then inserted into the quartz tube. The opposite end of the quartz tube is surrounded by a hollow tubular member 6 which is coaxially attached to the external hollow cylindrical tube 1. The member 6 is provided with a water circulation circuit 7. A sleeve 8 made of a refractory material is attached coaxially to the member 2 by connecting means 9. The tightness between this sleeve and

part 9 on one hand and part 6 on the other hand is performed by a number of seals 10. On the other end of part 6 a copper anode 11 provided, with a target metal pellet 12, inclined at 45° on the assembly centre-line, is fixed by means of a bolt.

This pellet 12 faces two apertures 13 pierced in parts 6 and 13a in the quartz cylinder 4. The common centre-line of these two apertures passes through the centre of pellet 12.

On the edge of aperture 13 is adjusted a capillary duct 14 upon which is placed an adjustment cock or micro-valve 15.

The socket 18 and the electrical connecting means 17 are arranged in order to permit the use of a standard voltage generator whose cable is adapted to feed a tube having a thermionic filament. In contrast to the thermionic filament tube no low voltage supply is necessary in the case of the tube according to the invention, so that a device comprising an ordinary lamp bulb 16 is available to be connected across the low voltage terminals of the cable through the conducting strips 16a and 16b.

The socket 18, adapted to receive the terminals of a cable used normally for a thermionic filament tube, is attached by means of washer 19. A connector 17 carried by the socket 18 is provided with passages for low voltage conductors which supply through the strips 16a and 16b the lamp bulb 16, and for high voltage conductors (not shown) which supply the electrodes 5 and 11.

An electron collector 20, borne by an insulating rod 20a, receives a fraction of the electronic beam emitted by anode 12 when a voltage is applied to cathode 5.

The high impedance current, collected by 20, is converted into low impedance voltage by the electronic assembly 21, having, for example, a vibrating condenser. The voltage issued from 21 is applied to a comparator 22, the output current of which controls a motor 23 which affects the adjustment of micro-valve 15.

This device operates in the following way:

The electrical field applied between cathode 5 and anode 11, distant from each other by two or three centimeters, causes the emission of electrodes drawn from the aluminium cathode 5.

Duct 14 feeds the space between the cathode and the anode with a gas such as argon, nitrogen or even dry air. By discharge at the output of capillary duct 14, there is a constant scanning of this space where the existing pressure is established according to the volume of the annular space comprised between tube 4 and 8 and the inter-electrode space and the pressure in the vacuum chamber surrounding the X-ray and electron generator tube.

The electrons drawn from cathode 5 meet molecules of gas and ionise the latter, creating thus a multiplying effect. All the electrons strike anode 11. Part of the electrons are directly back-scattered, another part penetrates slightly into pellet 12 and is back-scattered with a certain loss of energy, which enlarges the energy spectrum of the electrons. Another part of the electrons supplies energy to the pellet 12, simultaneously causing the emission of photoelectrons and X-rays.

Furthermore, there is heating and partly volatilization of the material of the pellet.

A part of the beam of electrons is collected by the collector 20.

The high impedance current is converted into low impedance voltage by the vibrating condenser amplifier 21 which delivers a voltage to the comparator 22 which, by a relay system controls, according to the difference voltage, a motor 23 having two ways of rotation.

This motor actuates the needle of a micro-valve 15, adjusting the flow of gas in the capillary duct 14.

The beam of electrons emitted is thus stabilized.

In another embodiment of the servo-system the current of electrons circulating between cathode 5 and anode 12 may be measured by means of a micro-ammeter A (FIG. 75

1A), the output current of which is converted into voltage and applied to the input of comparator 22.

Similarly, it is possible to measure by means of an X-ray sensitive device X (FIG. 1B) the flux of X-rays emitted by a target placed in the path of the electrons, when this target is provided either with a grid, or a matrix of constant composition.

FIG. 2 shows the assembly of the emitter tube in an X-ray spectrometer.

A vacuum chamber 24 or so-called diffractometry chamber, is connected to a second vacuum chamber 25, so-called emission chamber, in which is maintained an absolute pressure of about 10^{-3} torr, obtained by means of a mercury diffusion pump 27 driven by a vane-pump 28 and connected to the chamber 25 by said duct 26.

A Pirani gauge 29 is used to measure the absolute pressure. A capillary duct 30 is connected to an adjustable micro-valve 31 and to an emitter tube 32 of the type described in FIG. 1. This tube emits a flux of electrons and soft X-rays which strike a sample 33 energizing by X-fluorescence the heavy elements and emitting the X-ray spectrum of the light elements. The X-spectra characteristic of the elements which constitute the sample, after passing through a collimator such as the Soller slits 34, diffract themselves on a mobile analyser crystal 35 rotating around its axis as well as a gaseous flux meter 36 goniometrically mounted with a $1/2$ ratio.

The angle of diffraction is characteristic of the different elements to be analysed in the sample 33 and the intensity of the radiations collected enables quantitative analysis.

The detector 37, as well as the sample 33, receives a part of the flux of X-rays and electrons and delivers a signal to the integrator 38. The electrical signal is delivered to the servo-mechanism 39 with negative characteristic, which controls the solenoid valve 31. In particular, if the output flux from tube 32 tends to increase, the signal delivered by 37 increases, causing an increase in the electrical value issuing from 38. The negative characteristic servo-mechanism causes the flow of micro-valve 31 to decrease and consequently to reduce the output flux of tube 32. Inversely, a lowering of the flux produces the reverse effect and a stabilisation of the output flux of electrons and X-rays from tube 32.

What we claim is:

1. In a spectrometry apparatus comprising a vacuum pump and a vacuum chamber, a gas tube in said chamber for the emission of electrons and X-rays, means for introducing into said tube an ionizable gas the ionization of which results in a multiplication of the current within said tube, a sample holder in said chamber positioned in the path of emissions from said tube, Soller slits positioned to collimate the X-rays emitted by the sample, a rotatably mounted analyser crystal for diffracting the collimated X-rays, and a goniometrical flux meter responsive to rays diffracted by said crystal, the improvement according to which said emission tube contains an anode and a cathode located in a space in direct environmental communication with said vacuum chamber, a capillary duct connected to introduce into said gas tube a gas from outside said tube in the neighborhood of said cathode, gas flow control means in said duct, means to measure an electrical parameter which is characteristic of the operation of said gas tube, and servo means connected to said control means and said measuring means to control the flow of gas into said gas tube in response to variations in said electrical parameter in either direction from a predetermined value in order to stabilize the said parameter.

2. An apparatus according to claim 1 wherein the control means comprises a solenoid valve in the gas duct and said measuring means is responsive to the current flowing between said anode and cathode.

3. An apparatus according to claim 1 wherein the control means comprises a solenoid valve in the gas duct and said measuring means is responsive to the electron emission of the radiation output of the tube.

4. An apparatus according to claim 1 wherein the control means comprises a solenoid valve in the gas duct and said measuring means is responsive to the X-ray flux emitted by the sample under analysis.

5. Apparatus as claimed in claim 1 in which said emission tube comprises a hollow cylindrical external tube (1), an internal cylindrical member (2) inside said external tube, a quartz tube (4) attached to one end of said internal cylindrical member and containing at one end said anode and cathode, and a tubular hollow member (6) provided with a water circulation circuit, coaxially attached to said external tube (1) and encircling said quartz tube, said tubular hollow member (6) and said quartz tube being provided with aligned lateral apertures through which the space within said quartz tube in which said anode and cathode are located is in environmental communication with said vacuum chamber.

6. Apparatus as claimed in claim 5 in which said vacuum chamber is divided into two parts, one of which contains said crystal and flux meter, while the other contains said emission tube and sample holder, said Soller slits being positioned between said two parts.
